UNITED STATES PATENT OFFICE.

AUGUST F. WEHRLE, OF DENVER, COLORADO.

DESIGN FOR A SCARF-PIN.

SPECIFICATION forming part of Design No. 16,504, dated February 2, 1880.

Application filed September 19, 1885. Serial No. 177,626. Term of patent 7 years.

To all whom it may concern:

Be it known that I, AUGUST F. WEHRLE, of Denver, in the county of Arapahoe and State of Colorado, have invented a certain new and original Design for Scarf-Pins; and I do hereby declare the following to be a full, clear, and exact description of the invention, such as will enable others skilled in the art to which it pertains to make and use it, reference being had to the accompanying drawing, which form part of this specification.

My invention relates to new and original designs for scarf-pins, whereby the pin is given the shape of a candlestick scarf-pin, as will be more fully described hereinafter.

The accompanying drawing represents my invention.

A represents the pin, upon the upper end of which is the head B. This head is sharp and tapering at one end, and shows an oblong loop, C, at the other.

The round cylindrical piece I represents a candle, and which passes through the band D. Upon the top of the candle or part I is a device, J, which is to represent the flame of the candle. On the top of the pin A, the head B, or the band D is a hook, L, such as is used for securing a miner's lamp to the hat or cap. Also, attached to this pin is a hook.

Having thus described my invention, I claim—

The design for a scarf-pin herein shown and described, the same consisting of the pin A, having its head provided with the conventionalized representation of a candle, as set forth.

In testimony whereof I affix my signature in presence of two witnesses.

AUGUST F. WEHRLE.
